UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

BOILER

Application filed September 12, 1927. Serial No. 218,921.

This invention relates to a novel and improved construction of a boiler, and more particularly to the construction of a superheater. The invention will be best understood from the following description and the accompanying drawings. In the drawings, I have shown a selected embodiment of my invention, and referring thereto:

5

Fig. 1 is a longitudinal section through a superheater having my invention embodied therein;

Fig. 2 is a section on the line 2—2 of Fig. 1;

Fig. 3 is a section on the line 3—3 of Fig. 1;

Fig. 4 is a greatly enlarged fragmentary section through the outlet tube of a superheater header showing one form which my invention may take, this view being taken 20 on the line 4—4 of Fig. 5;

Fig. 5 is a view taken on the line 5—5 of Fig. 4;

Fig. 6 is a section on the line 6—6 of Fig. 4;

25 Fig. 7 is a view similar to Fig. 4, but showing a different embodiment of the invention, this view being taken on the line 7—7 of Fig. 8;

Fig. 8 is a view taken on the line 8—8 30 of Fig. 7.

Referring now to the drawings in detail, I have shown my invention as embodied in a superheater having two headers 1 and 2. Each header is made up of a plurality of sections, and, in this embodiment, the header 1 is shown as having the sections 3 and 4, and the header 2 as having the sections 5 and 6. The steam is admitted to the header section 3, as indicated by the arrow, and flows upwardly through the tubes 7 into the section 5 of the header 2, the tubes 7 forming outlet tubes for the header 1, and inlet tubes for the header 2. The steam then passes lengthwise of the header 2, and downwardly through the tubes 8 into the section 4 of the header 1, these tubes being outlet tubes for the header 2, and inlet tubes for the header 1. The steam then flows lengthwise of the section 4 of the header 1, and passes back to the header 2 through

the tubes 9, which are outlet tubes for the header 1 and inlet tubes for the header 2. This operation is repeated as many times as may be desired.

It has been found that outlet tubes disposed adjacent an inlet become rapidly burned out, because of the fact that the steam entering the header from the inlet, particularly when at a high velocity, will be carried past the adjacent outlet tubes by reason of the high velocity. This difficulty I have overcome by providing means which will cause the inertia of the steam to divert it into the adjacent tubes, in the desired amount.

55 The above means is best shown in Figs. 2 to 8, inclusive, and referring particularly thereto, it will be seen that I have provided a plurality of ferrules 10 in the outlet tubes adjacent the inlet of the particular header section. For the purposes of illustration, I have shown these ferrules as being placed in the five outlet tubes in each row of tubes nearest to the inlet. It will be understood, however, that this arrangement may be varied as found expedient.

60 It will be seen that each ferrule fits snugly within a tube where it may be retained by any suitable means, as by the frictional engagement between the ferrule and the tube. In Figs. 7 and 8 I have shown a ferrule 10' in a tube 7, at the point where this tube leaves the header 1. This ferrule comprises a sleeve 11 fitting snugly within the tube 7, and within the sleeve 11 is received a second sleeve 12 having an inwardly extending apron 13 which is adapted to catch and divert the steam which enters the header, the steam following the path indicated by the arrows. The inertia of the steam will cause it to be diverted into the ferrule, and thus into the tube, without substantial diminution of velocity.

65 Preferably the form shown in Figs. 7 and 8, or another form with a relatively large opening through the ferrule, is disposed in the tubes nearest to the inlet. In the tubes more remote from the inlet, ferrules of decreasing size of bore may be employed because of the fact that the velocity of the

steam will be decreased considerably before reaching those tubes. For example, I have shown in Figs. 4, 5 and 6, a ferrule 10" which, in this form, is shown as one piece of material having the bore 14 substantially parallel with the length of the header and with the direction of flow of the steam. Intersecting the bore 14, is a second bore 15 parallel to the axis of the tube, and it will be seen that this bore 15 is substantially smaller than the bore in the sleeve 12 of the ferrule 10". It will, of course, be understood that the different forms of ferrules shown may be used interchangeably, and that the bore in either form may be varied in size as may be found desirable. In both forms illustrated, it will be seen that the mouth of each opening is directed at least in part towards the direction from which the steam flows, or in other words toward the inlet. If so desired, the ferrules may be so disposed that the mouths of the openings therein will be set at an angle with the direction of flow of the steam, and by adjusting the degree of angularity, the amount of flow through the ferrules and through the superheater tubes can be regulated. A ferrule so disposed is shown in dotted lines in Fig. 8.

From the above it will be seen that I have devised means of novel and improved form which will readily divert steam to the outlet tubes disposed transversely of the header. This diversion prevents the steam from passing the tubes nearest to the inlet and insures a proper distribution of the steam between the different tubes leaving the header.

I claim:

1. In combination, a header having a steam inlet, a plurality of outlet tubes disposed at varying distances from said inlet, and ferrules in said tubes projecting into said header, each of said ferrules having means to divert steam into the corresponding tubes, the ferrules nearest the inlet being constructed and arranged to divert a greater amount of steam than those more remote from the inlet.

2. In combination, a header having a steam inlet, a plurality of outlet tubes disposed at varying distances from said inlet, and means to divert steam into the outlet tubes adjacent the inlet, said means being constructed and arranged to divert progressively smaller amounts of steam to the tubes as the distance of the tube from the inlet increases.

3. In combination, a header having a steam inlet and through which steam from said inlet flows longitudinally of the header, a plurality of outlet tubes extending transversely from the header and spaced longitudinally thereof, and ferrules extending into the header from at least some of said

tubes, the ferrules in the tubes nearest the inlet having larger openings than those in tubes more remote from the inlet.

4. In combination, a header having a steam inlet and through which steam from said inlet flows longitudinally of the header, a plurality of outlet tubes extending transversely from the header and spaced longitudinally thereof, ferrules extending into the header from at least some of said tubes, the ferrules in the tubes nearest the inlet having larger openings than those in tubes more remote from the inlet, and the mouths of said openings being disposed at least in part toward the inlet.

5. In combination, a header having a steam inlet and through which steam from said inlet flows longitudinally of the header, a plurality of outlet tubes extending transversely from the header and spaced longitudinally thereof, means extending into the header adjacent at least some of said tubes and forming mouths therefor, said mouths being directed at least in part toward the inlet, and the mouths nearest the inlet being larger than those more remote therefrom.

HOWARD J. KERR.
